US0D1065248S

(12) **United States Design Patent** (10) **Patent No.:** **US D1,065,248 S**
(45) **Date of Patent:** **** Mar. 4, 2025**

(54) **DISPLAY SCREEN OR PORTION THEREOF WITH GRAPHICAL USER INTERFACE**

(71) Applicant: **Google LLC**, Mountain View, CA (US)

(72) Inventor: **Christopher Norman**, Brooklyn, NY (US)

(73) Assignee: **Google LLC**, Mountain View, CA (US)

(**) Term: **15 Years**

(21) Appl. No.: **29/883,172**

(22) Filed: **Jan. 25, 2023**

Related U.S. Application Data

(60) Continuation of application No. 29/780,102, filed on Apr. 22, 2021, now Pat. No. Des. 980,250, which is a division of application No. 29/703,042, filed on Aug. 23, 2019, now Pat. No. Des. 927,507.
